UNITED STATES PATENT OFFICE

155,093

DESIGN FOR A RADIO ANTENNA

Wayne L. Leonard, Burbank, Calif.

Application May 25, 1948, Serial No. 146,580

Term of patent 3½ years

(Cl. D26—14)

To all whom it may concern:

Be it known that I, Wayne L. Leonard, a citizen of the United States, residing in Burbank, in the county of Los Angeles and State of California, have invented a new, original, and ornamental Design for a Radio Antenna, of which the following is a specification, reference being had to the accompanying drawing, forming part thereof.

Fig. 1 is a side elevational view of a radio antenna, showing my new design.

Fig. 2 is a front elevational view thereof.

Fig. 3 is an enlarged cross-sectional view as taken on line 3—3 of Fig. 1, as viewed in the direction of the arrows.

I claim:

The ornamental design for a radio antenna, substantially as shown.

WAYNE L. LEONARD.
